US00D486650S

(12) **United States Design Patent** (10) Patent No.: **US D486,650 S**
(45) Date of Patent: **** Feb. 17, 2004**

(54) **CAMOUFLAGE PATTERN FOR SHEET MATERIAL**

(75) Inventors: **Kellie Zupkofska**, Braintree, MA (US);
Anabela Dugas, Fall River, MA (US);
Richard Cowan, Franklin, MA (US);
Lynn D. Kellner, Yonkers, NY (US);
Michael Popov, Babylon, NY (US)

(73) Assignee: **Battelle Memorial Institute**,
Columbus, OH (US)

(**) Term: **14 Years**

(21) Appl. No.: **29/172,048**

(22) Filed: **Dec. 4, 2002**

(51) LOC (7) Cl. **05-06**

(52) U.S. Cl. **D5/32**

(58) Field of Search .... **D5/1, 2, 3, 6, D5/7, 8, 11, 15, 16, 19, 20, 23, 24, 25, 28, 32, 35, 36, 37, 39, 40, 43, 45, 47, 49, 50, 52, 53, 54, 55, 56, 57, 58, 59, 60, 61, 62, 63, 64, 66, 99; D2/749, 994; D6/582, 583, 595, 596, 598, 603, 604, 605, 606, 608, 613, 616, 617, 619, 622; D24/124, 125; D25/142, 152; 428/17, 18, 151, 154, 156, 171, 187, 198, 199, 542.2, 542.6, 904.4, 919; 5/413 AM, 709; D7/396.4, 396.5; 162/134, 231, 140; 156/209, 148**
